UNITED STATES PATENT OFFICE

2,504,724

SLICING MACHINE

Roy A. Perry, Santa Monica, Calif.

Application August 25, 1947, Serial No. 770,454

4 Claims. (Cl. 31—21)

1

This invention relates to new and useful improvements in slicing machines and the primary object of the present invention is to provide a machine for slicing butter and the like into small, uniform pats.

Another important object of the present invention is to provide a butter receptacle including novel and improved means for cutting and ejecting pats of butter therefrom.

A further object of the present invention is to provide a receptacle adapted to receive a stick of butter at each end thereof and including a slidable cutter mounted in the receptacle whereby upon a back and forth movement of the cutter, similar, uniform pats of butter are cut and ejected from each stick of butter and from each end of the receptacle.

A still further aim of the present invention is to provide a slicing machine that is simple and practical in construction, neat and attractive in appearance, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a perspective view of the present invention showing ice chambers applied thereto for use of the device in commercial eating establishments;

Figure 2 is a perspective view of the present invention for a family use;

Figure 3 is a transverse vertical sectional view taken substantially on the plane of section line 3—3 of Figure 2; and,

Figure 4 is a longitudinal vertical sectional view taken substantially on the plane of section line 4—4 of Figure 2.

Referring now to the drawing in detail, wherein for the purpose of illustration, there is disclosed a preferred embodiment of the present invention, the numeral 10 represents a substantially rectangular receptacle having transparent side walls 12, end walls 14 and a bottom wall 16. The lower ends of the end walls are similarly notched adjacent the bottom wall, to provide opposing guide openings or transverse slots 18. The side walls 12 are provided with longitudinal slots 20 that slidably engage a rod 22 having its ends bent to form eyes 24.

The numeral 26 represents a substantially

2

channel-shaped cutter having a web portion and spaced leg portions or flanges 28. The flanges 28 are provided with central apertures that receive the rod 22 for retaining the cutter in a fixed position to the rod with the web of the cutter spaced above and parallel to the wall 16. An ejector plate 30 is rigidly carried by the lower face of the cutter, at the center thereof adjacent rod 22, for a purpose which will later more fully be described.

Extending through apertures provided at the longitudinal center of the side walls, and adjacent their upper edges, is a cross rod 32 having its end bent downwardly in spaced parallelism to provide a pair of attaching arms 34 disposed on the outer faces of the side walls that frictionally engage eyes 24. A finger receiving lever 36 is rigidly carried by one of the arms 34, for actuating the rod 22.

It should be here noted, that the sharpened or beveled edges 38 of the cutter are disposed in a vertical plane with the inner faces of the end walls when the rod 22 is disposed at the longitudinal center of the slot 20, and that the lower edges of the flanges 28 of the cutter are spaced relative to the bottom wall.

In practical use of the device, a stick of butter is placed in each end of the receptacle and bears upon the upper face of the cutter, when the rod 22 is in the longitudinal center of the slot 20 and the arms 34 are disposed vertically. When the lever 36 is pulled downwardly in one direction, the cutter will slide forwardly in an opposite direction so that the stick of butter at one end of the receptacle will slide downwardly upon the bottom wall. Upon actuation of the lever 36 in an opposite direction, the cutter will slice a lower portion of the stick of butter and the ejector plate 30 will force the same through the slot 18 at that end of the receptacle into a suitable container. Simultaneously with the last operation, the other stick of butter will slide downwardly upon the bottom to be cut as the lever is again actuated. Hence by back and forth motion, similar and uniform pats of butter will be ejected from each end of the receptacle.

The device thus described and as best shown in Figures 2—4 inclusive is adapted for home use and may be inserted into an ice box with these sticks of butter in place thereto. However, for use in commercial eating establishments, it is preferred that supporting brackets 40 be secured to the end walls to support ice chambers 42, whereby the sticks of butter will remain in a

frozen state during the use of the device in cutting uniform pats of butter.

In view of the foregoing description taken in conjunction with the accompanying drawing it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A butter slicing machine comprising a substantially rectangular receptacle having a pair of side walls, a pair of end walls and a bottom wall, the end walls having opposing transverse guide slots adjacent the bottom wall, the side walls having opposing longitudinal slots adjacent the bottom wall, a transverse cutter supporting rod slidably mounted in said longitudinal slots, an elongated substantially channel shaped cutter having transverse cutting edges and a web carried by said rod for selective movement through the guide slots, means for actuating said rod, said rod rigidly carried by the said cutter and spaced from the web thereof for engaging an article sliced by the cutting edges of said cutter, an interconnecting means between said rod and said means for actuating said rod, the web of said cutter forming the sole supporting means for a pair of butter sticks placed in the receptacle when said cutter is disposed between said end walls.

2. A slicing machine comprising a substantially rectangular receptacle adapted to receive butter sticks, said receptacle having opposed transverse openings, an elongated substantially channel shaped cutter slideable through said openings having transverse cutting edges for alternately cutting articles in said receptacle, a transverse pusher rod carried by said cutter on the undersurface thereof, and manually operated means for reciprocating said cutter, said means including a transverse and rotatable shaft carried by said receptacle at the central portion thereof, a pair of hanger arms depending from said shaft, and means securing said hanger arms to said pusher rod.

3. The combination of claim 1 wherein said means for actuating said rod includes a cross bar, the side walls of said receptacle having central openings receiving said cross bar, said cross bar

having downwardly extending portions spaced outwardly of the side walls of said receptacle, said rod having terminal eyes receiving the downwardly extending portions of said cross bar, said cross bar constituting a spacing element for spacing two sticks of butter placed in said receptacle from each other and thereby preventing two sticks of butter placed in the receptacle from adhering together.

4. A butter slicing machine comprising a substantially rectangular receptacle having a pair of side walls, a pair of end walls and a bottom wall, the end walls having opposing transverse guide slots adjacent the bottom wall, the side walls having opposed longitudinal slots adjacent the bottom wall, a transverse cutter support slidably received in said longitudinal slots and having eye terminals projecting outwardly beyond said side walls, an inverted channel shaped butter cutter having a web and a pair of spaced legs, the legs of said cutter having apertures receiving said cutter support, said cutter having transverse cutting edges at its ends, the legs of said cutter bearing upon said bottom wall, said side walls having central openings, a cross bar received in said central openings for rotation, said cross bar having downwardly extending portions received in the eye terminals of said rod, said cross bar constituting a means for separating two sticks of butter inserted in said receptacle and preventing two sticks of butter placed in said receptacle from adhering together, said cutter constituting a sole supporting means for two sticks of butter placed in said receptacle when the downwardly extending portions of said cross bar are disposed substantially perpendicular to said cutter, and a finger grip fixed to one of said downwardly extending portions.
